1

The present invention relates to means for and method of scrambling speech signals, more particularly those in which secrecy in the transmission of messages, such as speech, is involved and known generally as speech scrambling in the art.

According to known methods of scrambling electrically transmitted signals, a signal current or voltage wave comprising a predetermined frequency band is subdivided, prior to its transmission, into a plurality of frequency sub-bands, which are interchanged by the aid of auxiliary displacement carrier oscillations in their relative positions within the original frequency band. Additionally, the frequencies of one or more sub-bands may be inverted by known means to increase the degree of secrecy obtained.

The present invention also relates to a scrambling method of this general type known as frequency substitution scrambling, and has for its main object to further increase the degree of secrecy obtained and to substantially prevent the deciphering or decoding of a scrambled message by an unauthorized listener or receiver.

With this general object in view, the invention involves basically the subdivision of a given signal frequency band, such as a speech frequency band, into a plurality of sub-bands which are mutually interchanged in accordance with the substitution scrambling method.

According to the present improvement, the thus obtained scrambled frequency band is divided into at least two secondary or partial frequency ranges which are mutually interchanged and at least one of which may be inverted, said secondary frequency ranges being so related to the primary scrambling sub-bands that their common limit or separating frequency or frequencies coincide with a frequency within one of said sub-bands. In other words, the limit or separating frequency of the partial ranges should not coincide with any of the limit frequencies of the primary scrambling sub-bands, as will become further evident from the following.

The invention, both as to its further objects and novel aspects, will become more apparent from the following detailed description taken in reference to the accompanying drawings forming part of this specification, and wherein:

Fig. 1 is a theoretical diagram illustrating the successive steps of converting a given speech frequency band into a final scrambled band in accordance with the invention.

Fig. 2 shows a practical system in block diagram form for carrying into effect the scrambling method illustrated in Fig. 1.

2

Figs. 3 and 4 are partial diagrams illustrating, respectively, a preferred multi-frequency generator and modulator or frequency transposing device suitable for use in connection with the invention.

Referring more particularly to Fig. 1, wherein the abscissae along the various horizontal lines represent frequency and the ordinates represent amplitude, an original speech frequency band *a* covering a range from 300 cycles to 2,700 cycles, which has been found in practice to be fully sufficient for the transmission of intelligible speech, is at first transposed or shifted to the range between 8,300 and 10,700 cycles by modulating it in the modulator *M*₁, Fig. 2, upon an auxiliary displacement carrier oscillation *u*₁ supplied by a multi-frequency or harmonic generator *G* and having a frequency *f*₁=8,000 cycles. By segregating, by means of band pass filter *F*₁, the upper side band from the output of modulator *M*₁, the frequency band *b* is obtained in a manner well understood. The frequency band *b* is in turn subjected to a further modulation in the modulator *M*₂ to which are applied in succession by means of a distributor *U* six auxiliary oscillations *u*₃, *u*₄ . . . *u*₈ also supplied by the harmonic generator *G* and having frequencies *f*₃=7,600 cycles, *f*₄=7,200 cycles, *f*₅=6,800 cycles, *f*₆=6,400 cycles, *f*₇=6,000 cycles, *f*₈=5,600 cycles, respectively.

In order to increase the degree of secrecy, it is desirable to change the sequence of application of the auxiliary oscillations *u*₃, *u*₄ . . . *u*₈ to the modulator *M*₂ by correspondingly connecting the distributor contacts to the supply leads from the generator *G*.

As a result of the modulation in modulator *M*₂, periodic lower side bands *c*₁, *c*₂ . . . *c*₈ are obtained successively displaced relative to the original band *a* by differences of $\frac{1}{8}$ of the latter, i. e., equal to 400 cycles. The signal bands *c*₁, *c*₂ . . . *c*₈ are amplified in a standard amplifier *A*₁. Each of the amplified signal frequency bands *c*₁, *c*₂ . . . *c*₃ is then divided into two partial frequency ranges separated at the fixed or separating frequency *t*, the latter amounting to 2,900 cycles, in the example shown. This separation is effected by means of an electrical switch consisting in the case illustrated of two filters *F*₂ and *F*₃ connected in parallel and having frequency passing ranges adjoining each other at the common separating frequency *t*. Filters *F*₂ and *F*₃ may be band-pass or low-pass and high-pass filters, respectively, of known design, as is readily understood. An essential requirement to

obtain a high degree of secrecy is the fact that within each of the frequency bands $c_1, c_2 \dots c_6$ there exists a different ratio between the partial ranges produced in accordance with the above. In other words, the individual frequency bands $c_1, c_2 \dots c_6$ is displaced periodically relative to the fixed frequency t in the manner clearly seen from the drawing.

According to the next step, the partial frequency ranges or primary sub-bands containing the lower frequencies of the bands $c_1, c_2 \dots c_6$ are in turn intermodulated in the modulator M_3 with a further auxiliary oscillation u_2 supplied by the generator G and having a fixed frequency $f_2=11,200$ cycles in the example illustrated. The resulting lower and accordingly inverted side bands obtained from this modulation are segregated by means of a band-pass filter F_4 .

Furthermore, the partial ranges or primary sub-bands of higher frequency of the speech frequency bands $c_1, c_2 \dots c_6$ are again intermodulated in the modulator M_4 with the respective auxiliary oscillations $u_3, u_4 \dots u_8$ and the upper side bands of the modulation product also segregated by the band-pass filter F_4 . In this manner, the output of filter F_4 supplies the six partially inverted speech frequency bands $d_1, d_2 \dots d_6$ all falling within the same frequency range of 8,300 to 10,700 cycles, corresponding to the passing range of the filter F_4 . As is understood, the primary sub-bands of the frequency bands $c_1, c_2 \dots c_6$ may be mutually interchanged by means of any one of the known methods and devices to increase the degree of secrecy obtained.

For the sake of simplicity, there has been illustrated in Fig. 1 only the further scrambling of the split or divided frequency band d_4 , it being understood that the further scrambling of the bands d_1, d_2, d_3, d_5 , and d_6 takes place in a substantially analogous manner. The frequency band d_4 is again periodically shifted into different frequency ranges by intermodulating it in the parallel connected modulators $M_{5a}, M_{5b}, M_{5c}, M_{5d}, M_{5e}, F_{5f}$ with auxiliary oscillations $u_3, u_4 \dots u_8$, whereby the lower side bands $e_1, e_2 \dots e_6$ are obtained which are mutually displaced by a distance of 400 cycles, that is, equal to one-sixth of the total initial speech frequency band or corresponding to the bands c_1 to c_6 . Sub-bands $g_1, g_2 \dots g_6$, each falling within the range of 2,700-3,100 cycles, are then segregated from each of the frequency bands $e_1, e_2 \dots e_6$ by means of identical band-pass filters $F_{5a}, F_{5b} \dots F_{5f}$, respectively. The sub-bands $g_1, g_2 \dots g_6$ are in turn shifted to produce an adjoining frequency band by modulation with the auxiliary oscillations $u_3, u_4 \dots u_8$ in the modulators $M_{6a}, M_{6b} \dots M_{6f}$, respectively. In this manner, the final and completely scrambled frequency band h falling within the range of 8,300 to 10,700 cycles is obtained. The final scrambled frequency band h , in addition to its sub-division into a pair of primary sub-bands, one of which is inverted, is thus additionally divided into a relatively larger number of secondary sub-bands $g_1, g_2 \dots g_6$, in such a manner that the limit frequencies of said secondary sub-bands each coincides with an intermediate frequency of the primary sub-bands or, in other words, that the separating frequency of the primary sub-bands coincides sequentially and periodically with a predetermined intermediate such as the center frequency of different secondary sub-bands $g_1, g_2 \dots g_6$.

Since the separating frequency of 2,900 cycles in the example illustrated at which the frequency

bands $c_1, c_2 \dots c_6$ are split or divided is exactly in the center of the frequency range of 2,700 to 3,100 cycles, which corresponds to the passing range of the filters $F_{5a}, F_{5b} \dots F_{5f}$, the sub-band g_4 in the final scrambled signal is comprised of two sub-band portions or ranges g_4' and g_4'' each having a band width equal to 200 cycles. Furthermore, in the example illustrated, sub-band portion g_4'' is uninverted, while sub-band portion g_4' is inverted and contains the lowest frequencies of the original speech frequency band a . An essential condition for the attainment of a maximum of secrecy is the fact that the lowest speech frequencies which are predominantly contributory to the intelligibility of speech are always contained in the sub-band portion g_4' of only 200 cycles band width.

It is understood that the separating frequency t may be so chosen as to coincide with any other frequency within the frequency range of the filters $F_{5a}, F_{5b} \dots F_{5f}$. In this latter case the sub-band portions g_4' and g_4'' will be of unequal width and the conditions are advantageously so chosen that the sub-band portion g_4'' has a narrower width than the sub-band portion g_4' .

The same scrambling as described in connection with the speech frequency bands d_4 will occur with all the other bands d_1, d_2, d_3, d_5, d_6 . Thus, for instance, in the case of the bands d_5 and d_2 , the corresponding sub-bands g_6 and g_2 , respectively, in the final scrambled signal h will be divided into corresponding sub-band portions, as will be readily understood.

In order to still further increase the degree of secrecy obtained, the auxiliary oscillations $u_3, u_4 \dots u_8$ are applied to the modulators $M_{5a}, M_{5b} \dots M_{5f}$ by way of the permutating device P , whereby their sequence is varied according to a prearranged schedule. In this case, the driving means for the permutator P and the distributor U should be operated in synchronism as indicated schematically by the dot-dash connection in the drawing. As a result, the sub-bands $g_1, g_2 \dots g_6$ will have their sequence mutually interchanged.

The final scrambled speech signal band h is shown to be applied to a further amplifier A_2 followed by a band-pass filter F_6 having a passing frequency range of 8,300-10,700 cycles. Finally, the frequency band h is subjected to a further modulation in the modulator M_7 with the auxiliary oscillation u_1 to return it to the original low frequency range of 300-2,700 cycles corresponding to the initial speech frequency band a and resulting in the finally scrambled signal band i within the same range. The scrambled signal band may then be applied by way of a further filter F_7 having a passing range of 300-2,700 cycles to a transmitting channel such as a telephone line or radio transmitter.

In order to reconstruct the original message in an intelligible manner at the receiving end, the same conversion steps as described but in reverse sequence are employed, using substantially the same apparatus as provided at the transmitter.

In the example described hereinabove, the initial speech frequency band is at first separated or split into two partial ranges and thereupon divided into a plurality of mutually interchanged sub-bands to produce a final scrambled signal. As is understood, the sequence of operation may be reversed, that is, the initial band may be first subjected to substitution scrambling by dividing it into a plurality of sub-bands, and

the thus scrambled signal then split into the two partial ranges in accordance with the present invention. It is furthermore possible to separate a scrambled signal comprising a plurality of interchanged sub-bands obtained by a substitution method, into more than two partial ranges, care being taken in accordance with the invention that the limit frequencies of said partial ranges do not coincide with any of the limit frequencies of the primary sub-bands in order to obtain the novel effects and increased degree of secrecy in accordance with the invention.

It is also possible to utilize the arrangement described in such a manner that the speech frequency band is repeatedly or successively separated into partial ranges to secure an added secrecy.

The various elements and parts required for carrying the invention into effect may be of standard design and construction well known in the art. This applies especially to the filters and amplifiers, all of which are common and standard equipment in communication systems. The multi-frequency generator G may also be of any known construction. A suitable form of such generator is shown in Fig. 3, comprising a tuning fork oscillator O feeding a harmonic generator A₃ in the form of a vacuum tube amplifier designed and operated to produce a highly distorted output wave form, such as by the provision of a high negative grid bias, as indicated in the drawing. By means of a plurality of filters N₁, N₂ . . . N₈ connected in the plate circuit of the tube, the auxiliary frequencies $u_1, u_2 \dots u_8$ are derived from the harmonic spectrum in the anode current.

The various modulators used for shifting or transposing the frequency bands to desired points on the frequency scale may also be of any type known in the art. A specially suitable form of modulator is shown in Fig. 4, comprising a balanced circuit of dry rectifiers, such as those of the copper oxide or selenium type well known in the art, wherein one of the signals to be intermodulated is applied to terminals 1, 1' and the other signal is applied to terminals 2, 2', the resultant product or output being derived from terminals 3, 3' in a manner well known.

While I have shown and described a desirable embodiment of my invention, it is understood that this disclosure is for the purpose of illustration and that various changes and substitutions of equivalent steps and elements for those herein shown and described may be made without departing from the spirit and scope of the invention as defined in the appended claims. The specification and drawings are accordingly to be regarded in an illustrative rather than a limiting sense.

I claim:

1. A system for secret transmission of speech comprising means for sequentially and periodically producing from an original speech frequency band a plurality of equal components each displaced with respect to the next one by equal frequency ranges being a fraction of the total band width of one over the number of components produced, means for splitting of said components into two partial frequency ranges at a common and fixed separating frequency, further means for shifting the respective partial ranges into a common frequency range of band width equal to the original speech frequency band and with one of said partial frequency ranges being inverted, to produce a plurality of

5 pre-scrambled frequency bands comprising partial ranges of varying relative width, means for in turn producing from each of said pre-scrambled frequency bands a plurality of relatively displaced components coinciding respectively with said first-mentioned components, band-pass filter means for segregating from said last-mentioned component equal bands of limited width equal to the above-mentioned fraction of

10 the total original frequency band and having upper and lower limit frequencies lying at both sides of said separating frequency, and means for unequally shifting the bands selected by said filter means to positions so as to adjoin each other and to form a final scrambled signal of band width equal to the original speech frequency band.

2. A system for secret transmission of speech comprising means for sequentially and periodically producing from an original speech frequency band a plurality of equal components each displaced with respect to the next one by equal frequency ranges being a fraction of the total band width of one over the number of components produced, means for splitting of said components into two partial frequency ranges at a common and fixed separating frequency, further means for shifting the respective partial ranges into a common frequency range of band width equal to the original speech frequency band and with one of said partial frequency ranges being inverted, to produce a plurality of sequential pre-scrambled frequency bands comprising partial ranges of varying relative width, means for in turn producing from each of said pre-scrambled frequency bands a plurality of relatively displaced components coinciding respectively with said first-mentioned components, band-pass filter means for segregating from said last-mentioned components equal bands of limited width equal to the above-mentioned fraction of the total original frequency band and having upper and lower limit frequencies lying at both sides of said separating frequency, and means for unequally shifting the bands selected by said filter means to positions so as to adjoin each other and to form a final scrambled signal of band width equal to the original speech frequency band.

3. A system for secret transmission of speech comprising means for sequentially and periodically producing from an original speech frequency band a plurality of equal components each displaced with respect to the next one by equal frequency ranges being a fraction of the total band width of one over the number of components produced, means for splitting of said components into two partial frequency ranges at a common and fixed separating frequency, further means for shifting the respective partial ranges into a common frequency range of band width equal to the original speech frequency band and with one of said partial frequency ranges being inverted, to produce a plurality of sequential pre-scrambled frequency bands comprising partial ranges of varying relative width, means for in turn producing from each of said pre-scrambled frequency bands a plurality of relatively displaced components coinciding respectively with said first-mentioned components, band-pass filter means for segregating from said last-mentioned components equal bands of limited width equal to the above-mentioned fraction of the total original frequency band and having upper and lower limit frequencies equally spaced from said separating frequency, and means for unequally

shifting the bands selected by said filter means to positions so as to adjoin each other and to form a final scrambled signal of band width equal to the original speech frequency band.

4. A system for secret transmission of speech comprising means for sequentially and periodically producing from an original speech frequency band a plurality of equal components each displaced with respect to the next one by equal frequency ranges being a fraction of the total band width of one over the number of components produced, means for splitting of said components into two partial frequency ranges at a common and fixed separating frequency, further means for inverting the lower partial frequency ranges and for shifting the respective partial ranges into a common frequency range of band width equal to the original speech frequency band and with one of said partial frequency ranges being inverted, to produce a plurality of sequential pre-scrambled frequency bands comprising partial ranges of varying relative width, means for in turn producing from each of said pre-scrambled frequency bands a plurality of relatively displaced components coinciding respectively with said first-mentioned components, band-pass filter means for segregating from said last-mentioned components equal bands of limited width equal to the above-mentioned fraction of the total original frequency band and having upper and lower limit frequencies lying at both sides of said separating frequency, and means for unequally shifting the bands selected by said filter means to positions so as to adjoin each other and to form a final scrambled signal of band width equal to the original speech frequency band.

5. In a method of secret signalling, the steps of subdividing a given signal frequency band into at least two primary sub-bands one of which is inverted, and furthermore dividing the pre-scrambled frequency band into a relatively larger number of secondary sub-bands the limit frequencies of which coincide with different intermediate frequencies of said primary sub-bands.

6. In a method of secret signalling, the steps of subdividing a given signal frequency band into at least two primary sub-bands frequency-inverting at least one of said sub-bands, and furthermore dividing the pre-scrambled frequency band into a relatively larger number of secondary sub-bands with the separating frequency of said primary sub-bands coinciding with an intermediate frequency of one of said secondary sub-bands.

7. In a method of secret signalling, the steps of subdividing a given signal frequency band into at least two primary sub-bands one of which is inverted, and furthermore dividing the pre-scrambled frequency band into a relatively larger number of secondary sub-bands with the separating frequency of said primary sub-bands coinciding with the center frequency of one of said secondary sub-bands.

8. In a method of secret signalling, the steps of subdividing a given signal frequency band into at least two primary sub-bands one of which is inverted, furthermore dividing the pre-scrambled signal frequency band into a relatively larger number of secondary frequency sub-bands the limit frequencies of which coincide each with a different intermediate frequency of said primary sub-bands.

9. In a method of secret signalling, the steps of subdividing a given signal frequency band into

two primary sub-bands one of which is inverted, furthermore dividing the pre-scrambled frequency band into a number greater than two of secondary frequency sub-bands the limit frequencies of which coincide with different intermediate frequencies of said primary sub-bands.

10. In a method of secret signalling, the steps of subdividing a given signal frequency band into two primary sub-bands one of which is inverted, furthermore dividing the pre-scrambled frequency band into a number greater than two of secondary frequency sub-bands the limit frequencies of which coincide with different intermediate frequencies of said primary sub-bands, and sequentially and periodically varying the ratio of relative width of said primary sub-bands.

11. A system for secret signalling comprising scrambling means for subdividing a given signal frequency band into at least two primary sub-bands one of which is inverted, and further means for additionally dividing the pre-scrambled frequency band into a relatively larger number of secondary frequency sub-bands the limit frequencies of which coincide with different intermediate frequencies of said primary sub-bands.

12. A system for secret signalling comprising scrambling means for subdividing a given signal frequency band into at least two primary frequency sub-bands one of which is inverted, and further means for additionally dividing the pre-scrambled frequency band into a relatively larger number of secondary frequency sub-bands, the separating frequency of said primary sub-bands coinciding with the center frequency of one of said secondary sub-bands.

13. A system for secret signalling comprising scrambling means for subdividing a given signal frequency band into at least two primary frequency sub-bands one of which is inverted with the relative width of said primary sub-bands changing sequentially and periodically, and further means for additionally dividing the pre-scrambled frequency band into a relatively larger number of secondary frequency sub-bands the limit frequencies of which coincide with different intermediate frequencies of said primary sub-bands.

14. A system for secret transmission of speech comprising frequency substitution scrambling means for subdividing a given speech frequency band into a pair of primary frequency sub-bands one of which is inverted with the relative width of said primary sub-bands changing sequentially and periodically, and further means for additionally dividing the pre-scrambled speech frequency band into a number greater than two of secondary frequency sub-bands the limit frequencies of which coincide with different intermediate frequencies of said primary sub-bands, whereby the separating frequency of said primary sub-bands coincides with an intermediate frequency of one of said secondary sub-bands.

15. A system for secret signalling comprising scrambling means for subdividing a given signal frequency band into a pair of primary sub-bands, means for frequency inverting one of said sub-bands, means for sequentially and periodically varying the relative band width of said primary sub-bands further means for additionally dividing the pre-scrambled signal frequency band into a number greater than two of secondary frequency sub-bands the limit frequencies of which coincide with different intermediate frequencies of said primary sub-bands, and means operated in synchronism with said last-mentioned means.

for periodically varying the interchanging code of said secondary sub-bands.

16. A system for secret transmission of speech comprising scrambling means for subdividing a given speech frequency band into a pair of primary sub-bands, means for frequency inverting one of said sub-bands, means for sequentially and periodically varying the relative band width of said primary sub-bands further means for additionally dividing the pre-scrambled frequency band into a number greater than two of secondary frequency sub-bands the limit frequencies of which coincide with different intermediate frequencies of said primary sub-bands, means for frequency inverting part of said secondary frequency bands, further means for sequentially and periodically varying the relative band width of said primary sub-bands, and means operated in synchronism with said last mentioned means for varying the interchanging code of said secondary sub-bands.

17. The method of secret signalling consisting in subdividing, by sequential steps of frequency substitution scrambling, a given signal frequency band into groups of different numbers of partially inverted frequency sub-bands, the limit frequencies of the sub-bands resulting from one scrambling step coinciding with intermediate frequencies of the sub-bands resulting from another scrambling step.

18. A system for secret transmission of speech comprising scrambling means for subdividing a given speech frequency band into a pair of primary sub-bands, means for frequency inverting one of said sub-bands, further means for additionally dividing the pre-scrambled frequency band into a number greater than two of partially inverted secondary frequency sub-bands, means for sequentially and periodically varying the relative band width of said primary frequency sub-bands whereby the separating frequency of said primary sub-bands successively coincides with the center frequencies of different secondary sub-bands, and further means operated in synchronism with said last-mentioned means for varying the interchanging code of said secondary sub-bands.
